MAGNETIC CORE STRUCTURE AND METHOD
OF ASSEMBLINGRoy H. Dierstein, Fort Wayne, Ind., assignor to
General Electric Company, a corporation of
New York

Application September 3, 1938, Serial No. 228,378

5 Claims. (Cl. 175—356)

My invention relates to magnetic cores such as are used in transformers and reactors. One form of magnetic core which has been used extensively includes an outer hollow shell with a winding leg extending across the opening and fitting so tightly between opposite sides of the shell as to hold it securely in place. The shell and the winding leg have been formed of superposed laminations, and it has been found that if the winding leg laminations are cut or punched from the same positions in the outer shell laminations that they are to occupy when assembled, then the two parts of the core will fit tightly and securely when they are forced together. The winding or 10 windings are of course preferably placed around the winding leg before it is forced into position in the outer shell. It has been found that when the winding leg laminations are punched from the same positions that they are finally to occupy in the outer shell, the fit between the winding leg and the shell is so tight that the edges of the laminations may sometimes be damaged as they rub over each other when forced together, and this is particularly true of laminations which are formed of the more inexpensive 15 and soft materials. It has thus been sometimes necessary to use rather expensive material in order to avoid too much damage from this cause.

The general object of the invention is to provide an improved magnetic core and an improved method for forming the magnetic core having a winding leg held in place by a forced fit in an outer shell, but avoiding any substantial damage to the material during the assembly.

35 The invention will be better understood from the following description taken in connection with the accompanying drawing in which Fig. 1 is a perspective view of a transformer including a magnetic core formed in accordance with the invention, and Fig. 2 is a perspective view showing the transformer partially assembled and a machine or tool for assembling it. Like reference characters indicate similar parts in both figures of the drawing.

45 The transformer 10 shown in Fig. 1 includes a magnetic core 11 having a winding leg 12 fitting tightly between the yokes 13 and surrounded by windings 14. The outer ends of the yokes 13 are integrally connected by outer legs 15 to provide 50 return paths for the magnetic flux. The laminations forming the winding leg 12 are cut or punched from the same positions which they are finally to occupy in the laminations of the yokes 13 so that they will be held securely in position 55 when the two parts of the core are assembled.

The laminations including the yokes 13 are formed with notches in the outer edges of the yoke portions so that when assembled these notches will be in alignment to form a notch 16 extending across each outer surface of the yokes. 5 The sides of the notches diverge inwardly from the outer surface of each yoke so that they may be engaged by projections 17 on the inner surfaces of blocks 18 and 19 mounted on a suitable flat support 20. The projections 17 fit into the notches 16 in dovetail fashion so that the blocks 18 and 19 and the yokes 13 are held securely together. The block 18 is secured to the support 20 while the other block 19 is movable to permit it to be pulled away from the block 18 by a lever 15 21 to increase the spacing between the yokes. The block 19 may be operated by foot or otherwise by means of a link 22.

In assembling the magnetic core 11, the laminations of the winding leg 12 are cut or punched 20 from the positions which they are finally to occupy between the yoke portions 13 of the outer magnetic shell. The windings 14 are placed around the winding leg 12, and the laminations of the outer shell are dropped into place between 25 the blocks 18 and 19 with their notches 16 engaged by the projections 17 of the blocks. The lever 21, which engages a rod 23 extending between opposite sides of the block 19, is operated to force the block 19 away from the block 18. 30 This forces the two projections 17 of the two blocks apart and applies pulling forces to the outer surfaces of the yokes 13 to spring the yokes 13 sufficiently away from each other to permit the winding leg 12 with its windings 14 to be 35 placed in position between the two yokes 13 without the necessity of using undue force and consequently without damage to the laminations as they rub together. In some cases it may be advisable to apply sufficient force to the movable 40 block 19 to spread the yokes 13 enough to permit the winding leg 12 to drop freely into place between the yokes. It is obvious, however, that it may often be satisfactory to apply only sufficient force to the block 19 to permit the winding leg 12 to be forced into position between the yokes 13 without damage to the laminations. Any force applied by the lever 21 to the block 19 45 will of course reduce the friction between the ends of the winding leg 12 and the yokes 13 and permit the winding leg 12 and the outer magnetic shell to be more easily assembled and with less injury to the laminations. After the winding leg 12 is in place, the block 19 is released to permit 50 55

the yokes 13 to grip the winding leg and hold it securely in place.

The invention provides not only a simple and convenient method of assembling the core parts, but an improved core as well because of the more perfect fit between the parts and the absence of injury and distortion to the edges of the laminations. The presence of the notches 16 in the outer surfaces of the yokes 13 opposite the ends 10 of the winding leg is obviously not objectionable because they do not interfere to any substantial degree with the magnetic flux in the core. The notches 16 also permit the yokes to be easily engaged and spread apart at any time after assembly if repair or replacement of the windings is necessary.

The invention has been explained by describing and illustrating a particular transformer and a particular method of forming it, but it will be obvious that changes may be made without departing from the spirit of the invention and the scope of the appended claims.

What I claim as new and desire to secure by Letters Patent of the United States is:

25 1. The method of forming a magnetic core of flat stacked laminations having a winding leg and spaced integrally connected yokes with the winding leg fitting tightly between the yokes, said method including the steps of applying pulling forces to the outer surfaces of the yokes to increase the spacing between them, placing the winding leg between the yokes without substan-

tial friction therebetween, and releasing the yokes to permit them to grip the winding leg.

2. The method of forming a magnetic core of punched and stacked laminations having spaced integrally connected yokes and a winding leg 5 fitting tightly between the yokes, said method including the steps of applying pulling forces to the yokes to increase the spacing therebetween by edgewise distortion of the laminations, placing the winding leg between the yokes without 10 such friction between said leg and said yokes as to cause appreciable injury to the abutting edges of the laminations, and releasing the yokes to permit them to grip the winding leg.

3. A magnetic core including a winding leg 15 and spaced integrally connected yokes, said winding leg fitting tightly between the yokes, and the yokes having dovetail notches across their outer surfaces.

4. A magnetic core including a winding leg 20 and spaced integrally connected yokes, said winding leg fitting tightly between the yokes, and each yoke having a dovetail notch across its outer surface opposite the adjacent end of the winding leg.

25 5. A magnetic core including a hollow shell forming spaced yokes and outer core legs integrally connecting said yokes, and a winding leg fitting tightly between the yokes, the yokes having dovetail notches across their outer surfaces. 30

ROY H. DIERSTEIN.
